UNITED STATES PATENT OFFICE.

ZDENKO FREUND, OF NEWARK, NEW JERSEY.

DESIGN FOR A VEIL-PIN, RIBBON-PIN, OR SIMILAR ARTICLE.

No. 39,741.

Specification for Design.

Patented Jan. 5, 1909.

Application filed September 18, 1908. Serial No. 453,713. Term of patent 7 years.

To all whom it may concern:

Be it known that I, ZDENKO FREUND, a citizen of the United States, residing at Newark, in the county of Essex and State of New Jersey, have invented a new, original, and ornamental Design for a Veil-Pin, Ribbon-Pin, or Similar Article, of which the following is a specification, reference being had to the accompanying drawing, forming part hereof.

The figure is a plan view of a veil pin, showing my new design.

I claim:

The ornamental design for a veil pin, ribbon pin, or similar article, as shown.

ZDENKO FREUND.

Witnesses:

PETER MEYER,
ELMER VOM EIGEN.
